BUTTER APPLICATOR

George H. Smith, 3360-D Norton Ave.,
Lynwood, Calif. 90262

Filed Apr. 29, 1969, Ser. No. 16,932

Term of patent 14 years

Int. Cl. D8—02

U.S. Cl. D44—29

Fig. 1.

Fig. 2.

Fig. 3.

Fig. 4.

Fig. 5.

FIG. 1 is a top plan view of a butter applicator, showing my new design.

FIG. 2 is an elevational side view.

FIG. 3 is a bottom view.

FIG. 4 is a perspective view showing the two components of the applicator separated for better illustration.

FIG. 5 is a fragmentary cross-sectional view as taken on the line 5—5 of FIG. 3.

I claim:

The ornamental design of a butter applicator, substantially as shown.
